US00D536173S

(12) **United States Design Patent** (10) **Patent No.:** **US D536,173 S**
(45) **Date of Patent:** **** Feb. 6, 2007**

(54) **LANYARD CONNECTOR SURFACE**

(75) Inventors: **Bryan K. Hicks**, Salt Lake City, UT (US); **Brandon Robert Mackay**, Salt Lake City, UT (US)

(73) Assignee: **Snugz USA, Inc.**, Salt Lake City, UT (US)

(**) Term: **14 Years**

(21) Appl. No.: **29/259,457**

(22) Filed: **May 8, 2006**

Related U.S. Application Data

(60) Division of application No. 29/201,442, filed on Mar. 16, 2004, now Pat. No. Des. 520,241, which is a division of application No. 09/931,658, filed on Aug. 16, 2001, now Pat. No. 6,711,785, and a division of application No. 09/931,392, filed on Aug. 16, 2001, now abandoned, which is a continuation-in-part of application No. 09/541,297, filed on Apr. 3, 2000, now abandoned, which is a continuation-in-part of application No. 09/538,956, filed on Mar. 31, 2000, now abandoned, which is a continuation-in-part of application No. 29/106,139, filed on Jun. 9, 1999, now Pat. No. Des. 437,485, which is a continuation-in-part of application No. 29/105,931, filed on Jun. 4, 1999, now Pat. No. Des. 422,142, and a continuation-in-part of application No. 29/105,930, filed on Jun. 4, 1999, now Pat. No. Des. 426,063.

CLAIM

The ornamental design for a lanyard connector surface, as shown and described.

DESCRIPTION

FIG. 1 is a perspective view of a lanyard connector surface of the present invention;

FIG. 2 is a top plan view of the lanyard connector surface of the present invention;

FIG. 3 is a bottom plan view of the lanyard connector surface of the present invention;

FIG. 4 is a rear end view of the lanyard connector surface of the present invention;

FIG. 5 is a front end view of the lanyard connector surface of the present invention; and,

FIG. 6 is a side view of the lanyard connector surface of the present invention, the opposing side view being a mirror image thereof.

The objects shown in broken lines are shown for environmental purposes only and form no part of the claimed design.

All of the material from the parent applications that is essential to the claimed design is included herein. Any material in the parent applications that is not present herein forms no part of the claimed design.
